UNITED STATES PATENT OFFICE.

HERBERT J. A. SKIPP, OF EAST PROVIDENCE, RHODE ISLAND.

DESIGN FOR AN ARTICLE OF MANUFACTURE.

51,050.

Specification for Design.

Patented July 17, 1917.

Application filed April 3, 1917. Serial No. 159,556. Term of patent 3½ years.

To all whom it may concern:

Be it known that I, HERBERT J. A. SKIPP, a citizen of the United States, residing at East Providence, in the county of Providence and State of Rhode Island, have invented a certain new and useful Design for an Article of Manufacture, of which the following is a specification.

The figure is a plan view of a badge illustrating my new design.

The design comprises in its upper portion the representation of an eagle flanked on

either side by downwardly directed United States pennants embracing or forming an elliptical background in which is the bust of the present President of the United States. Along the bottom margin of the design is the representation of a ribbon scroll.

I claim:

The ornamental design for an article of manufacture, as shown and described.

HERBERT J. A. SKIPP.
